UNITED STATES PATENT OFFICE.

CHARLES THOMAS MASON, OF SUMTER, SOUTH CAROLINA, ASSIGNOR TO SPLITDORF ELECTRICAL COMPANY, OF NEWARK, NEW JERSEY, A CORPORATION OF NEW JERSEY.

IGNITION-DYNAMO.

1,325,257.

Specification of Letters Patent. Patented Dec. 16, 1919.

Application filed March 15, 1916. Serial No. 84,379.

To all whom it may concern:

Be it known that I, CHARLES THOMAS MASON, a citizen of the United States, residing at Sumter, in the county of Sumter and State of South Carolina, have invented certain new and useful Improvements in Ignition-DYNAMOS, of which the following is a specification, reference being had to the accompanying drawing.

10 This invention relates to ignition dynamos commonly termed magnetos, and has for its object the production of a simple, cheap and efficient machine, easily constructed, of few parts, and adapted for either high or 15 low tension work.

A further object is to eliminate all moving wire, and to make the moving parts very light, so they have comparatively little inertia, thereby making this machine particularly desirable as an oscillator. There 20 are other objects that will hereinafter more fully appear.

In the accompanying drawings, Figure 1 is a front elevation of the driving end of 25 the machine, Fig. 2, a side view of the same, Fig. 3 an end view partly in section, and Figs. 4, 5, and 6, views showing the path of the magnetic flux through the machine when the operating parts thereof are in different positions.

Like figures of reference denote the same parts wherever they are shown.

1, denotes a suitable permanent magnet or magnets attached in any suitable manner, 30 such as by the screws, 2 and 2^a, to the pole pieces 3 and 3^a, the latter being attached to a suitable non-magnetic base 4. Carried upon and secured to this base is the stationary core 5, carrying a suitable winding 35 6, one end of which may be connected to the core 5 and the other end brought out of the machine in any suitable manner.

Carried upon the core 5 and pivotally connected thereto (or pivoted to pole pieces 40 3, and 3^a) are the flaps 7, 8, 9, and 10, of magnetic material, normally held in their closed positions shown in Fig. 3 by suitable springs 11, 12, 13 and 14. These flaps normally serve to bridge the air gaps between 45 the pole shoes 3 and 3^a and the poles of the core 5, the flaps extending the complete length of the pole shoes from one end of the magneto to the other.

The ends of the flaps or the shafts carrying the same project outwardly from the 55 driving end of the magneto, and are arranged as shown in Fig. 2 and carry at their outer end suitable cams or rollers indicated at 15, 16, 17 and 18. These rollers are engaged by the cams 19 and 20 carried on a 60 suitable shaft 21, journaled in the end plate 22.

The cams 19 and 20 are so shaped and positioned in relation to the rollers on the flaps that they operate the same in pairs as hereinafter described, thereby causing a change in the direction of the flow of the flux through the core 5. It is obvious however that more than two cams may be used, and these may be so shaped as to open the flaps 70 any desired number of times per revolution, or in any desired sequence.

From the foregoing description will be obvious that the winding in this magneto is stationary; that the moving parts consist of the shaft 21, carrying the two light cams 19 and 20; that these cams engage the light rollers and flaps, and that the entire operating mechanism is very light and therefore easy to drive.

It is obvious that the shaft 21 may be oscillated and I consider this machine particularly well adapted for use as an oscillating magneto.

Fig. 4 shows the magneto with the flaps 85 in the non-operative position, whereby they bridge the air gaps between the pole pieces 3 and 3^a and the core 5, the flux then passes from the N to the S pole of the magnet as shown by the arrows, without passing 90 through the core 5 of the winding and consequently no current is generated.

At Fig. 5, one pair of flaps 7 and 10 have been opened, thereby breaking one path for the flux, which must now flow from the N 95 pole of the magnet to pole piece 3, across flap 9, through the core 5, through flap 8 to pole piece 3^a and to the S pole of the magnet, thereby subjecting the winding 6 to a magnetic influence.

The shaft being now further revolved, flaps 7 and 10 close and flaps 8 and 9 open, thereby suddenly reversing the direction of the flux through the core of the armature 5. The flux now travels from the N pole of the 105 magnet to pole piece 3 to the flap 7, through

- core 5, to flap 10, to pole piece 3^a and to the S pole of the magnet. This sudden reversal of the flux through the core 5, generates a current in the winding 6 wound thereabout in a well known manner. It will be noted that the flaps make and break the magnetic circuit by direct contact, eliminating all air gaps therein, and thereby greatly increasing the efficiency.
- 10 In magnetos as commonly heretofore constructed, the windings have been placed upon a rotating armature, and it was necessary to have an air gap between this armature and the adjacent pole pieces; or the 15 armature and pole pieces were both stationary, and a movable member acted between them. Here also air gaps would exist, and as air gaps greatly cut down the efficiency of a machine of this type, their elimination 20 in my invention is a feature of importance. I make the hinge between the flaps and the core 5 of the armature as good mechanically as it is possible to make it, so as to provide as good a path as possible for the flux.
- 25 A further path is provided by the springs 11, 12, 13 and 14.
- It will be apparent to those skilled in the art that accurate fitting in a machine of this description is reduced to a minimum; that 30 the greatest accuracy required is in connection with the cams 19 and 20, so they will cause the oppositely disposed flaps, 7 and 10, and 8 and 9 to close and open relatively at the right time and in unison.
- 35 I have shown and described a so called "low tension magneto". It is readily seen that a high tension machine can be made by the addition of a circuit breaker, condenser and secondary winding; and as such additional parts and their arrangement are 40 readily understood I do not describe them here.
- And while I have shown the preferred embodiment of my invention, it will be understood that I do not limit myself to the 45 precise form herein described as many modifications may be made without departing from the invention I claim herein.
- I claim:
- 50 1. An ignition dynamo comprising a stationary core body and poles thereon and a winding on the body portion, a magnet having poles spaced apart from said core poles, flux controlling flaps adapted to simultaneously bridge the gaps between all of said poles, and means for actuating said flaps so that the magnetic flux is directed alternately in a divided path through all the flaps and the core ends and a single path through 55 two flaps and the core body.
2. An ignition dynamo comprising a stationary core having poles and a winding therebetween, a magnet having poles spaced apart from said core poles, flux conducting flaps adapted to simultaneously bridge the 60 gaps between all of said poles and in extended surface contact therewith, and means for actuating said flaps so that the magnetic flux is directed first in a divided path through all the flaps and the core ends and 70 then in a single path through two flaps and the core body.
3. An ignition dynamo comprising a stationary core having a winding and poles, a magnet having poles spaced apart from 75 said core poles, separate movable flux conducting hinged flaps adapted to simultaneously bridge each core pole to the opposite adjacent magnet poles and to maintain extended contact therewith, and means 80 for actuating said flaps whereby the flux through the core may be alternately reversed in direction.
4. An ignition dynamo comprising a stationary core having a generating winding 85 thereon and poles attached thereto, a magnet having its poles spaced apart from said core poles, magnetic conducting flaps simultaneously bridging all the gaps between said poles, and means for actuating said flaps, 90 including a cam and rollers on said flaps, so that the magnet flux is successively reversed in direction through said core.
5. An ignition dynamo comprising a base, a magnet supported thereby, a stationary 95 core supported on the base and carrying a generating winding, an end plate secured to said base, magnetic conducting members simultaneously bridging all the gaps between said magnet and core and means supported 100 wholly by said end plate for actuating said conducting members so that the magnet flux is caused to shift rapidly through said core and winding.
6. An ignition dynamo comprising a base, 105 a magnet supported thereby, a stationary core supported on said base and carrying a generating winding, an end plate secured to said base, conducting flaps simultaneously bridging all the gaps between said magnet 110 and core, spring means acting on said flaps whereby they are normally held in contact with said poles, and means supported by said end plate for actuating said flaps to direct the magnetic flux successively in reverse 115 direction through said core and winding.
7. An ignition dynamo comprising a stationary shuttle type core having a winding thereon and polar extremities outside said winding, a substantially U-shaped magnet 120 having poles arranged laterally adjacent said core polar extremities, movable flux conducting flaps adapted to simultaneously bridge all the gaps between the magnet poles and the core polar extremities, spring means tending to hold said flaps in said bridged position and means for actuating said flaps to direct the magnetic flux through said core 125 whereby a current is generated in said winding.

8. An ignition dynamo comprising a stationary core having a generating winding thereon and poles attached thereto, a magnet having poles spaced apart from said core poles, magnetic conducting members simultaneously bridging all the gaps between said poles, and means for moving said magnetic members so as to successively reverse the flux through said core and winding. 10
- 5 In testimony whereof I hereunto affix my signature.

CHARLES THOMAS MASON.
